Primary Examiner—Cathron C. Brooks*Assistant Examiner*—Austin Murphy*(74) Attorney, Agent, or Firm*—Keith R. Derrington(57) **CLAIM**

The ornamental design for a rotary mechanized tool, as shown.

DESCRIPTION

FIG. 1 is a side view of the rotary mechanized tool in one embodiment;

FIG. 2 is a top view of the rotary mechanized tool of FIG. 1;

FIG. 3 is a bottom view of the rotary mechanized tool of FIG. 1;

FIG. 4 is a frontal view of the rotary mechanized tool of FIG. 1; and,

FIG. 5 is a rear view of the rotary mechanized tool of FIG. 1.
